UNITED STATES PATENT OFFICE.

BLANCHE C. SHIELLS, OF NEENAH, WISCONSIN.

DESIGN FOR A DARNING-LAST.

SPECIFICATION forming part of Design No. 34,132, dated February 26, 1901.

Application filed January 28, 1901. Serial No. 45,144. Term of patent 14 years.

To all whom it may concern:

Be it known that I, BLANCHE C. SHIELLS, a citizen of the United States, residing at Neenah, in the county of Winnebago and State of Wisconsin, have invented and produced a new and original Design for Darning-Lasts, of which the following is a specification.

In the accompanying drawings, Figure 1 is a perspective view of a darning-last embodying my design, showing the concavity in the side and the concavity in the smaller end of the last. Fig. 2 is a perspective view thereof, showing another view of the concavity in the side and showing also the concavity in the larger end of the last.

The leading features of my design are an egg-shaped body A, having a concavity *a* in the smaller end or point of the body, a concavity *b* in the larger end or butt of the body, and a concavity *c* in the side of the body. 20

I claim—

The design for a darning-last, substantially as herein shown and described.

In testimony whereof I have hereunto subscribed my name.

BLANCHE C. SHIELLS.
